UNITED STATES PATENT OFFICE.

ROBERT S. SCOTT, OF KANSAS CITY, MISSOURI.

RAIL-TIE AND FASTENING MEANS.

No. 884,867.

Specification of Letters Patent.

Patented April 14, 1908.

Application filed May 13, 1907. Serial No. 373,467.

To all whom it may concern:

Be it known that I, ROBERT S. SCOTT, a citizen of the United States, residing at Kansas City, in the county of Jackson and State 5 of Missouri, have invented new and useful Improvements in Rail-Ties and Fastening Means, of which the following is a specification.

This invention relates to a rail tie and fastening means, the object of the invention being to provide a structure of this character which is comparatively light, yet strong, easy to make, and wherein the rails can be readily and quickly laid, and, when laid, can be solidly and firmly held against all possibility of spreading.

In the drawings accompanying and forming part of this specification I show in detail one effective form of embodiment of the invention, which, to enable those skilled in the art to practice said invention, will be set forth at length in the following description, while the novelty of the invention will be included in the claims succeeding said description.

Referring to said drawings: Figure 1 is a perspective view of the tie with one rail fastened in place and one shoe separated from the tie. Fig. 2 is a longitudinal sectional view of one end of the tie, the rail on the tie being in cross section. Fig. 3 is a transverse sectional side elevation of the parts shown in Fig. 2 and as seen from the right in said latter figure.

Like characters refer to like parts throughout the several figures.

The tie is denoted in a general way by 2 and, while it may be made of any desirable material, I prefer to make it of metal as, in this way, comparative lightness and strength are assured. The tie near the ends thereof is laterally widened as at 3, the rails, one of which is shown and is designated by 4, crossing these laterally widened portions 3. The tie along its opposite sides is shown as provided with downwardly-extending flanges as 5 extending longitudinally of the tie, and these flanges between their ends are illustrated as furnished with downwardly-extending wings as 6. The respective wings 6 and flanges 5 are represented as united by webs or flanges as 7, said webs or flanges 7 being also united with the body of the tie, as clearly shown in Fig. 2.

If desired, the several parts to which I have hereinbefore referred may be made in

one piece, for example, by casting, and steel can be advantageously utilized for this purpose. The invention, however, does not reside in the use of any particular material, but rather in certain structural features. A tie made as hereinbefore described is very strong and it is chambered in its under side to receive ballast, whereby it can be held in position in a steady manner. I prefer to mount 65 upon the tie at the laterally-widened portions thereof, plates as 8, and these plates are less in width than the bases of the rails, although they directly support in part said bases, as best indicated in Fig. 2. These 70 plates 8 are held in place by rivets or similar means as 9, the shanks of the rivets projecting vertically through perforations in the plates 8 and body of the tie 2, respectively, the said rivets having hooked or inwardly-bent upper ends which, when the rivets are in their operative positions, overlie the inner portions of the bases of the respective rails. The butts or lower ends of the rivets are shown as headed to hold them in place. 80 When the tie is made these rivets preferably form a permanent part of the same.

In operation the tie is positioned at the desired place and the rails are laid on the two plates 8 and are then moved sidewise or toward each other to carry the inner portions of their bases solidly under the hooks of the rivets 9. This, however, does not hold the rails. For this purpose I prefer to utilize shoes as 10, said shoes being shown as provided with downwardly-extending arms as 11 which, when the shoes are in operative relation, are adapted to straddle the wings 6. The bodies of the shoes are shown as provided with rows of pins or studs designated, 95 respectively, by 12, while tail-pieces as 13 of the shoes may be furnished with similar pins designated, respectively, by 14. All the pins or studs 14 extend downward. The downwardly-extending arms 11 to which I 100 have referred may be furnished with similar pins as 15, the latter, however, extending horizontally or inwardly. I prefer to make the two shoes of some resilient material and to utilize the several pins to which I have referred for holding the shoes in interlocked relation with the tie 2, the tie being provided with suitable sockets or seats to receive the pins and which seats may be of any suitable character, for example, they may be made 110 in the form of perforations, and, for simplicity, all of said perforations will be de-

noted by the character 16. It will be understood, of course, that there are perforations in the body of the tie and that the wings 6 also have like perforations. When the rails 5 are slipped under the spikes as previously described, the shoes 10 are applied to the tie upon the outer sides of the rails and are then advanced toward each other. When the several pins to which reference has been 10 made come opposite their co-operating perforations they will, owing to the resiliency of the shoes or plates 10, spring into said perforations, so as to hold the shoes securely in place.

15 The shoes are projected under the rail, as clearly indicated in Fig. 2, and their thickness equals that of the plates 8 to which I have referred, by reason of which the rails are held level. I provide, therefore, a simple 20 and positive means of holding the two shoes to the tie. The rivets 9 prevent movement of the rails toward each other, while, to obviate outward movement of said rails, the shoes are provided with hooks or inturned 25 lips as 17 which engage over the outer sides of the bases of the rails. The tail-pieces 14 to which I have referred may each be, as shown in Fig. 2, slightly upwardly and outwardly bent or curved so that a tool can be 30 inserted under these bent or curved portions to facilitate when necessary the removal of the shoes or the separation of the bodies thereof from the body of the tie. The arms 11 can be disconnected from the tie by an 35 outward pressure. Under actual conditions the two shoes are held securely in position, and they, with the spikes to which I have referred, effectually prevent movement of the rails toward or from each other. It is possible, however, owing to the resiliency of the 40 shoes or plates 10, to remove the same when occasion requires by the use of a proper implement.

What I claim is:

45 1. The combination of a tie, rail-supporting ribs on the tie, rail-holding spikes con-

nected with the ribs, and rail-supporting resilient shoes provided with rail-engaging means, said shoes being resilient and being provided with pins, the tie having seats into which said pins can be sprung to hold the 50 shoes to the tie.

2. The combination of a tie, rail-holding shoes provided with downwardly-extending arms to fit the opposite sides of the tie, said 55 shoes having rail-engaging hooks and also having pins on the under side thereof, said arms having pins on the inner side thereof, and the tie having seats into which the pins can be sprung by the resiliency of the shoes. 60

3. The combination of a tie having rail-supporting plates, rail-engaging rivets for holding the plates in place, and shoes of the same depth as the plates to fit under the rails and provided with hooks to engage the rails, 65 said shoes being resilient and having depending arms to fit the sides of the tie, the shoes and arms being provided with pins, and the tie having seats into which said pins can be sprung by the resiliency of the shoes. 70

4. A metal tie having flanges along its opposite sides, said flanges being provided with depending wings, and webs uniting the flanges and connected with the body of the tie. 75

5. The combination of a tie and resilient rail-holding means, the latter having means to hold the same in interlocking connection with said tie and against movement longitudinally thereof. 80

6. The combination of a tie and a resilient rail-holding shoe straddling the tie and in interlocking connection with said tie to prevent movement of the shoe longitudinally of the tie. 85

In testimony whereof I have hereunto set my hand in presence of two subscribing witnesses.

ROBERT S. SCOTT.
